US0D1093392S

(12) United States Design Patent (10) Patent No.: US D1,093,392 S
Dellinger et al. (45) Date of Patent: * Sep. 16, 2025

(54) DISPLAY SCREEN OR PORTION THEREOF
WITH GRAPHICAL USER INTERFACE

- (71) Applicant: Apple Inc., Cupertino, CA (US)
- (72) Inventors: Richard Dellinger, San Jose, CA (US); Jonathan P. Ive, San Francisco, CA (US); Wan Si Wan, Sunnyvale, CA (US)
- (73) Assignee: Apple Inc., Cupertino, CA (US)
- () Term: 15 Years
- (21) Appl. No.: 29/824,706
- (22) Filed: Jan. 26, 2022

CLAIM

The ornamental design for a display screen or portion thereof with graphical user interface as shown and described.

DESCRIPTION

FIG. 1 is a front view of a display screen or portion thereof with graphical user interface showing the claimed design; and,

FIG. 2 is another embodiment thereof.

The outermost broken lines in the figures show a display screen or portion thereof, and form no part of the claimed design. The other broken lines in the figures show portions of the graphical user interface that form no part of the claimed design.

1 Claim, 1 Drawing Sheet
